DOOR CONSTRUCTION

Julius I. Byrne, Detroit, Mich.

Application April 30, 1937, Serial No. 140,052

19 Claims.

(Cl. 20—19)

The invention relates to door constructions and refers more particularly to door constructions of relatively large area and adapted for use in airport hangars, craneway entrances, and the like.

The invention has for one of its objects to provide an improved door construction which will sustain either an internal or external wind pressure at all times without any connection between the door member and the jambs of the opening. The invention has for another of its objects to provide an improved door construction the opening and closing movements of which are controlled in a manner to provide for its movement to either open or closed position without binding. The invention has for further objects to provide a door construction comprising a door member which during its movement to open position has first a rectilinear upward movement and subsequently a combined upward and tilting movement and which during its movement to closed position has first a combined downward and tilting movement and finally a rectilinear downward movement; to provide means for assuring both the upward and downward movements at the proper times during the opening and closing of the door member; and to provide a door construction which will effectively close the opening.

These and other objects of the invention will become apparent from the following description, taken in connection with the accompanying drawings, in which:

Figure 1 is a front elevation of a door construction showing an embodiment of my invention;

Figures 2, 3, 4, 5 and 6 are cross sections respectively on the line 2—2, 3—3, 4—4, 5—5 and 6—6 of Figure 1;

Figure 7 is an enlarged front elevation of a closure panel and the adjacent part of the door member;

Figure 8 is a cross section on the line 8—8 of Figure 7;

Figure 9 is a section taken substantially on the line 9—9 of Figure 3;

Figure 10 is a view similar to Figure 3 showing the door construction in open position;

Figure 11 is a section taken substantially on the line 11—11 of Figure 10.

The door construction illustrated in the present instance is designed for use in an airport hangar having an opening of relatively large area. While the dimensions of the opening may vary considerably, the length in the construction

illustrated is approximately 150 feet and the height is approximately 40 feet. The door may be made of a number of operating sections and the sections may be opened and closed as units or together. In the present instance there are two door sections 1 and 1', which are formed alike, but reversely arranged end for end. Each door section comprises the door member 2, the frame of which is made up of the pairs of vertical members or stiles 3 and the horizontal members or rails 4, all rigidly secured together. The upper portion of each door member is formed with the slots or openings 5 which extend downwardly from its top between the adjacent vertical members or stiles 3 of each pair. The remainder of the upper portion is preferably made solid by securing plates 6 to the frame. The lower portion of each door member, with the exception of the individual door 7, is preferably made solid by securing suitable plates 8 and 9 to the frame. The intermediate portion 10 of each door member between the pairs of vertical members or stiles is preferably glazed, while the intermediate portion 11 between the vertical members or stiles of each pair is preferably made solid by extending the plates 9 upwardly.

When the door member is in closed position, the slots or openings 5 are closed by the closure panels 12. Each panel is formed of the plates 13 and 13' at the outside of the associated vertical members or stiles 3 of each pair. Laterally spaced vertical bars 14 extend longitudinally at the inside of and are rigidly secured to the plate 13. The bars 14 extend upwardly beyond the plate and inside the building directly behind the supporting member over the door opening and are pivotally connected to the overhead framework 15 of the building by the fixed pivot pin 16. The panel plates 13 and 13' are pivotally connected together by the pin 17, which also serves to pivotally connect the panel formed of these plates to the door member with lost motion only in a direction parallel to the door member. The lost motion connection is formed by the rollers 18 journaled upon the ends of the pin 17 and the laterally spaced tracks 19 extending vertically of and secured to the door member and engaged by the rollers. The construction is such that it provides for moving the door member vertically upward during the first portion of its movement from closed position to open position since at this time the tracks 19 may move over the rollers 18. This vertically upward movement may vary, but preferably is approximately 5 inches, which is sufficient to disengage the po-

sitioning means 20 at the bottom of the door member from the cooperating positioning means 21 located in the floor. In the present instance, the positioning means 20 comprises the arms 22 which cross each other and have their upper ends pivotally connected to the bottom horizontal member or rail forming the frame of the door member and their lower free ends engageable with the positioning means 21 and more particularly the side walls 23 of the sockets 24 formed in the floor. The positioning means 20 and 21 are located at intervals to properly position the bottom of the door member throughout its length, regardless of internal or external wind pressure.

15 For raising each door member, I have provided the linear suspension members 25, the traction drums 26 and the electric motor 27 which is connected to the drums to drive the same in either direction by a self-locking worm drive. 20 The linear suspension members are cables which are connected at intervals to the outside face of the door member. These connections are all in the same horizontal line, preferably at a point midway of the opening height. The cables run 25 vertically upwardly from the connections and over the sheaves 28 which are mounted upon the overhead framework 15 inside the building directly beyond the supporting member over the door opening. The cables then extend to the traction drums 26, from which they then extend over the sheaves 28 and are connected to the vertically movable counterweights 30.

35 For bracing the door member at all times so that it will sustain either an internal or an external wind pressure and for also controlling the movement of the door member so that when being moved to open position it will first have a vertically upward movement and then have a combined upward and tilting movement and when 40 being moved to closed position it will first have a combined downward and tilting movement and finally a vertically downward movement, I have provided the following construction. 31 are back braces at the inside of the door member pivotally connected at their lower ends to the pairs of vertical members or stiles 3 preferably midway of the opening height and substantially in line with the connections between the cables and the door member. The upper ends of these back 45 braces are pivotally connected to the trolleys 32 which are movable rectilinearly upon the tracks 33 rigidly supported upon the overhead framework 15. These tracks preferably incline inwardly and downwardly. Associated with each 50 back brace is the fulcrum lever 34 which extends at the inside of the door member and is pivotally connected at its upper end to the overhead framework 15 by the pivot pin 16. The lower end of the fulcrum lever is pivotally connected 55 at 35 to the back brace 31 midway of its length, which is approximately twice the length of the fulcrum lever. This fulcrum lever compels angular movement of the back brace and also lateral movement thereof during either the opening or 60 closing movement of the door member. Furthermore, the construction is such that the pivotal connection between the back brace and the door member moves vertically, thereby avoiding the necessity of any connection between the door member and the jambs at the sides of the opening. 65 Associated with each back brace 31 and fulcrum lever 34 are the guide struts 36, which together with the back brace positively controls the combined upward and tilting movement of 70 the door member. The guide struts 36 are pivot-

ally connected at their upper ends to the trolley 32 so that the upper ends of the guide struts and the upper ends of the associated back brace move laterally in unison. The lower ends of the guide struts having a pivotal lost motion connection with the associated closure panel 12. This lost motion connection comprises the guides 37 upon the lower end of the panel plate 13 at its inside and the rollers 38 upon the lower ends of the guide struts and engaging the guides. The lost motion is sufficient to permit the required vertical movement of the door member, either during the first portion of its opening movement or during the final portion of its closing movement.

15 In operation, the door member during the first portion of its movement from closed position, as illustrated in full lines in Figure 3, to open position moves vertically upwardly a distance to disengage the cooperating positioning means 20 and 21. During this time, the tracks 19 move 20 vertically over the rollers 18 and the rollers 38 move vertically upwardly along the guides 37, this latter being caused by the laterally inward movement of the trolleys 32. This movement of the trolleys is caused by the angular movement 25 of the back braces 31 upon the fulcrum levers 34 and also the angular movement of the latter. It will be noted that the pivotal connections between the back braces and the door member move vertically upward and that the pivotal connections 35 between the back braces and the fulcrum levers move inwardly and upwardly. Upon continuing the opening movement of the door member after it has moved vertically upwardly, the guide struts 36 act positively upon the closure 35 panels 12, which in turn act positively upon the upper portion of the door member to tilt the same inwardly. When the door member has assumed a fully open position, it extends substantially horizontally with the pivotal connections between 40 the back braces and the door member substantially vertically above their original positions. At this time, the inside of the door member forms its lower surface and the outside of the closure panel plates 13 form their lower surfaces, these 45 plates being above the door member. It will be apparent that during this opening movement, the fulcrum levers will extend through the slots or openings formed in the door member, these fulcrum levers and their associated guide struts and back braces being located so that the fulcrum levers are in alignment with the slots or openings when the door member is in closed position. It will be seen that when the door member is 50 being moved to closed position the electric motor 55 will be driven in the opposite direction to allow the door member to return by gravity. By reason of the connections and particularly by reason of the guide struts and their connections to the closure panels and the trolleys and the connections between the closure panels and the door member, the desired closing movement of the door member is positively secured. It is apparent that both the opening and closing movements are secured without binding occurring.

65 For the purpose of weathering the joint between a jamb 39 and the adjacent door member 1, I have secured to the jamb and the end vertical member or stile 3 of the door member the flexible U-shaped sealing members 40, the bases 70 of which are adapted to contact. For the purpose of weathering the joint between adjacent door members, I have provided upon the adjacent end vertical members or stiles of these door members the same sealing construction comprising the 75

flexible U-shaped sealing members 41 having their bases adapted to contact.

For the purpose of assuring the vertically upward and vertically downward movements of the door members respectively during the first portion of the opening movement thereof and during the final portion of the closing movement thereof, I have provided locking rollers 42 upon each fulcrum lever 34 and a cooperating locking 10 cam 43 upon each of the associated pairs of guide struts 36. Each locking cam provides a curved endface 44 engageable with the associated roller. The construction is such that during the opening movement the end faces of the cams 15 engage the rollers during the initial portion of the movement to compel the door member to move vertically upward the desired extent, after which movement the rollers 38 are approximately at the tops of the guides 37. Also during the closing 20 movement of the door member the end faces of the locking cams become engaged with the rollers at the time vertical downward movement of the door member is to occur. To maintain the rollers 38 at the tops of the guideways 37 to thereby 25 secure a predetermined lateral inward movement of the portions of the closure panels to which the guide struts are connected and consequently to secure a predetermined inward tilting of the upper portion of the door member 30 upon continued opening movement, the cams 43 are formed with the curved bottom faces 45 which are engageable with the associated rollers 42 immediately after they leave the end faces. It is apparent that the parts function in a corresponding manner during the movement of the door member to closed position. The bottom faces connect or merge directly into the end faces so that there is no noticeable interval between the functioning of these faces.

40 To assure continued predetermined lateral inward movement of the portions of the closure panels to which the guide struts are connected and to assure continued predetermined inward tilting of the upper portion of the door member, further provision is made for assuring positive guiding support for the door member during the opening thereof while the cam members and the associated rollers are no longer functioning. In detail, I have provided upon the guide struts 36 and preferably coaxial with the rollers 38 the rollers 38' and I have also provided the channel guides 34' upon the lower end portion of each fulcrum lever 34, the rollers 38' being adapted to engage in the associated channel guides 34'. During the disengagement of the rollers 42 from the bottom faces 45 of the cams 43 the rollers 38' are entering the upper ends of the channel guides 34' so that when the rollers 42 are being disengaged from the cams 43 the rollers 38' are being engaged with the channel guides 34'. While the functioning of the parts has been described in connection with the movement of the door member to open position, it will be seen that the parts function in a corresponding manner during the movement of the door member to closed position.

It will be seen that as a result of the above organization, the desired predetermined movement of the door member from its fully closed position to its fully open position is assured.

What I claim as my invention is:

1. In a door construction, the combination with a door member having a combined upward and tilting movement to open position and means for moving said door member, of other means con-

trolling the path of upward movement of a portion of said door member and other means pivotally connected to a portion of said second mentioned means and connected to another portion of said door member for compelling lateral movement thereof. 5

2. In a door construction, the combination with a door member having a combined upward and tilting movement to open position, of a brace having a connection with said door member intermediate its top and bottom, means cooperating with said brace for compelling upward movement of its connection with said door member, a guide strut having a connection with said door member vertically spaced from said first mentioned connection, and means associated with said brace and actuating said guide strut for compelling lateral movement of its connection with said door member relative to the first mentioned connection. 10 15 20

3. In a door construction, the combination with a door member having a combined upward and tilting movement to open position, said door member having a slot in its upper portion, of a panel for closing said slot, a brace connected to said door member intermediate its top and bottom, means comprising an angularly movable lever operatively connected to said brace for compelling the connection between said brace and door member to move substantially vertically, said lever being movable through the slot in said door member during movement of said door member to open position, and a guide strut movable laterally by said brace and having an operative connection with said panel. 25 30 35 40

4. In a door construction, the combination with a door member having an initial upward movement and a subsequent combined upward and tilting movement to open position, said door member having a slot in its upper portion, of a panel for closing the slot, a brace connected to said door member intermediate its top and bottom, said brace being angularly movable and having an end remote from said door member movable laterally, a fulcrum lever operatively connected to said brace to compel said movement thereof, said lever being adapted to extend through the slot in said door member during movement thereof to open position, a guide strut movable laterally with said remote end and having a lost motion connection with said panel, and cooperating means upon said lever and guide strut for compelling said initial upward movement of said door member. 45 50 55

5. In a door construction, the combination with a door member having a combined upward and inward tilting movement to open position, a fulcrum lever extending at the inner side of said door member, a brace extending at the inner side of said door member and operatively connected at its lower end portion to said door member intermediate its top and bottom and also operatively connected intermediate its ends to said fulcrum lever, said brace having its upper end portion movable inwardly through a predetermined path during the movement of said door member to open position, and a strut extending at the inner side of said door member and operatively connected at its lower end portion to said door member above the operative connection of said brace to said door member, said strut having its upper end portion movable inwardly in unison with the upper end portion of said brace. 60 65 70 75

6. In a door construction, the combination with a door member having a combined upward and

inward tilting motion while moving to open position, a brace at the inner side of said door member and operatively connected at its lower end to said door member intermediate its top and bottom, said brace having its lower end movable upwardly and its upper end movable inwardly through predetermined paths during the movement of said door member to open position, and means operatively connected to the upper end portion of said brace and to the upper portion of said door member above the connection between said brace and door member for compelling inward tilting of the upper portion of said door member.

15 7. In a door construction, the combination with a door member adapted to move upwardly and tilt inwardly to open position, said door member having a vertical slot in its upper portion, a panel at the outside of said door member for closing said slot, said panel being pivotally connected at its lower end to said door member and being pivotally connected at its upper end to a stationary pivot, a brace at the inside of said door member pivotally connected at its lower end to said door member intermediate its top and bottom, said brace having its lower end movable vertically upwardly and its upper end movable inwardly during the movement of said door member to open position, means for guiding the upper end of said brace, a lever extending at the inside of said door member and pivotally connected at its lower end to said brace intermediate its ends and also pivotally connected at its upper end to a stationary pivot, said lever being adapted to extend through the slot in said door member during the movement of said door member to open position, and a guide strut at the inside of said door member operatively connected at its upper end to the upper end of said brace and having a pivotal lost motion connection at its lower end to said panel.

8. In a door construction, the combination with a door member having a combined rectilinear and lateral movement to open position and means for moving said door member, of other means determining the path of rectilinear movement of a portion of said door member, and other means pivotally connected at one of its ends to a portion of said second mentioned means and at its other end to a portion of said door member and determining the path of lateral movement of said last mentioned portion of said door member, whereby said door member moves through a predetermined path with a combined rectilinear and lateral movement to open position.

55 9. In a door construction, the combination with a door member having a combined rectilinear and lateral movement to open position and means for moving said door member, of linkage determining the path of rectilinear movement of a portion of said door member, and other linkage pivotally connected at one end to another portion of said door member and at its other end to a portion of said first mentioned linkage to determine the path of lateral movement of said last mentioned portion of said door member, whereby said door member moves through a predetermined path with a combined rectilinear and lateral movement to open position.

70 10. In a door construction, the combination with a door member having a combined upward and tilting movement to open position, of a brace having a connection with said door member intermediate its top and bottom, means cooper- 75 ing with said brace for compelling upward move-

ment of its connection with said door member, a guide strut having a connection with said door member vertically spaced from said first mentioned connection, means associated with said brace and actuating said guide strut for compelling lateral movement of its connection with said door member relative to the first mentioned connection, and means controlling the movement of said second mentioned connection between said guide strut and door member.

10 11. In a door construction, the combination with a door member having a combined upward and tilting movement to open position, of a brace connected to said door member intermediate its top and bottom, said brace being angularly movable and having an end remote from said door member movable laterally, a pivotal fulcrum lever operatively connected to said brace to compel movement thereof, a co-pivotal member operatively connected to said door member, a guide strut movable laterally with said remote end and having a lost motion connection with said last mentioned member, and positive control guiding means for said lost motion connection.

15 12. In a door construction, the combination with a door member having a combined upward and tilting movement to open position and means for moving said door member, of linkage controlling the path of upward movement of a portion of said door member, and a member connected to said linkage and another portion of said door member and operable under tension to compel lateral movement of said last mentioned portion during opening movement of said door member and also operable under compression to compel lateral movement of said last mentioned portion during closing movement of said door member.

20 13. In a door construction, the combination with a door member having a combined upward and tilting movement to open position, of linkage connected to an intermediate portion of said door member and adapted to control the path of upward movement of said portion, and a guide strut having one end connected to a laterally movable portion of said linkage and having its other end operatively connected to a portion of said door member spaced vertically from the point of connection of said linkage to said door member and operable upon movement of said linkage to compel lateral movement of its connection with said door member relative to the connection of said linkage to said door member.

25 14. In a door construction, the combination with a door member having a combined upward and tilting movement to open position, of a brace extending at the inner side of the door member and operatively connected at its lower portion to said door member intermediate its top and bottom and having its upper portion movable laterally inwardly through a predetermined path during the movement of said door to open position, a fulcrum lever pivotally connected at its upper end to a stationary pivot and having its lower end pivotally connected to said brace intermediate the ends of the latter, a second lever pivotally connected at its upper end to a stationary pivot and having its lower end operatively connected to said door member at a point spaced upwardly from the connection of said brace to said door member, and a strut extending at the inner side of said door member and operatively connected to said second lever adjacent the point of connection of said second lever to said door member, said strut having its upper end opera- 30 35 40 45 50 55 60 65 70 75 80 85 90 95

tively connected to the upper end of said brace and laterally movable therewith to compel tilting of the door member.

15. In a door construction, the combination with a door member having a combined upward and tilting movement to open position, of a brace pivoted at its lower end to said door member, means for guiding the upper end of said brace inwardly in a predetermined path, a lever having a fixed pivotal mounting at one end and also having a pivotal connection with said brace intermediate the ends of the latter, a strut pivoted at one end to said door member at a point spaced from the connection of said brace to said door member and having a portion thereof movable inwardly upon inward movement of the upper end of said brace to compel tilting movement of said door member.

16. In a door construction, the combination with a door member having a combined upward and tilting movement to open position, of a brace pivoted at its lower end to said door member, means for guiding the upper end of said brace inwardly in a predetermined path, a lever having a fixed pivotal mounting at one end and also having a pivotal connection with said brace intermediate the ends of the latter, a strut pivoted at one end to said door member at a point spaced from the connection of said brace to said door member and having a portion thereof movable inwardly upon inward movement of the upper end of said brace to normally cause tilting movement of said door member, and cam means associated with one of said levers and engageable with a portion of the other lever to compel the door member to move upwardly a predetermined distance prior to the tilting movement thereof.

17. In a door construction, the combination with a door member having a combined upward and tilting movement to open position, of a brace

pivoted at its lower end to said door member, means for guiding the upper end of said brace inwardly in a predetermined path, a lever having a fixed pivotal mounting at one end and also having a pivotal connection with said brace intermediate the ends of the latter, a strut pivoted at one end to said door member at a point spaced from the connection of said brace to said door member and having a portion thereof movable inwardly upon inward movement of the upper end of said brace, a follower carried by one of said levers, and a cam carried by the other of said levers and engageable with said follower, said cam having a portion compelling a predetermined initial upward movement of said door member during the opening thereof and having another portion controlling the tilting movement of said door member subsequent to said upward movement.

18. In a door construction, a door comprising pivotally connected sections, linkage controlling the path of upward movement of a portion of said door spaced from the zone of the pivotal connection between said sections, and a member having a portion thereof connected to said linkage and another portion connected to the portion of said door in the zone of the pivotal connection between said sections and compelling lateral movement thereof.

19. In a door construction, a door comprising a pair of sections pivotally connected together, means controlling the path of upward movement of a portion of said door spaced from the zone of the pivotal connection between said sections, and a member connected to the portion of said door in the zone of the pivotal connection between said sections and operated upon movement of said door to compel lateral movement of said last mentioned portion of said door.

JULIUS I. BYRNE. 40
